(57) **CLAIM**

The ornamental design for a display screen with animated graphical user interface, as shown and described.

DESCRIPTION

FIG. 1 is a first image in a sequence of a display screen with animated graphical user interface, showing the new design; FIG. 2 is a second image thereof; FIG. 3 is a third image thereof; FIG. 4 is a fourth image thereof; FIG. 5 is a fifth image thereof; FIG. 6 is a sixth image thereof; and, FIG. 7 is a seventh thereof.

The broken lines of uneven length show the display screen and form no part of the claimed design. The appearance of the display screen with animated graphical user interface sequentially transitions between the images shown in FIGS. 1-7. The process or period in which one image transitions to another forms no part of the claimed design.
